(57) **CLAIM**

The ornamental design for a hair straightener, as shown and described.

DESCRIPTION

FIG. 1 is a perspective view of a hair straightener, embodying my new design;

FIG. 2 is a left side elevational view thereof;

FIG. 3 is a right side elevational view thereof;

FIG. 4 is a front elevational view thereof; the rear elevational view being a mirror image thereof;

FIG. 5 is a top plan view thereof; and,

FIG. 6 is a bottom plan view thereof.

The broken lines shown in the drawings illustrate portions of the hair straightener and form no part of the claimed design.
